UNITED STATES PATENT OFFICE.

CHARLES J. NEWBURGH, OF CHICAGO, ILLINOIS.

DESIGN FOR A GLASS COVER-PLATE FOR HEADLIGHT-LAMPS.

54,858.

Specification for Design.

Patented Apr. 13, 1920.

Application filed February 5, 1918. Serial No. 215,536. Term of patent 14 years.

To all whom it may concern:

Be it known that I, CHARLES J. NEWBURGH, a citizen of the United States, residing at Chicago, in the county of Cook and State of Illinois, have invented a new, original, and ornamental Design for Glass Cover-Plates for Headlight-Lamps, of which the following is a specification, reference being had to the accompanying drawing, forming part thereof.

The figure is a face view of a glass cover plate designed for use in the front of automobile headlights or similar lamps, illustrating my new design. One side of this

plate is polished and has a corrugated or ribbed surface, while the other side is formed with a broad semi-circular frosted band A and a narrow circular frosted band B concentric with the band A, the field within the band B being formed with a series of vertical grooves C. The appearance of the plate is substantially the same whether viewed from one side or the other.

I claim:

The ornamental design for a glass cover plate for headlight lamps, as shown and described.

CHARLES J. NEWBURGH.
